UNITED STATES PATENT OFFICE.

JAMES MADISON CLAYBROOK, OF HUNTSVILLE, ALABAMA.

DESIGN FOR A BUTTON.

SPECIFICATION forming part of Design No. 25,306, dated March 31, 1896.

Application filed January 11, 1896. Serial No. 575,183. Term of patent 3½ years.

To all whom it may concern:

Be it known that I, JAMES MADISON CLAYBROOK, a citizen of the United States, residing at Huntsville, in the county of Madison and State of Alabama, have invented and produced a new and original Design for Buttons, of which the following is a specification, reference being had to the accompanying drawing, showing a part thereof.

10 My invention relates to a new and original design for buttons.

The accompanying drawing is a view of a button embodying my design.

15 The leading feature of my design comprises a round button having a perfectly smooth periphery, with the representation thereon of a gold bug in the center of its outer surface, a

ring encircling this bug, and two gold stars in the annular panel formed between the ring and the periphery of the button.

20 A represents the button having two concentric rings 1 and 2. Within the inner ring is the representation of the bug 3. In the annular panel 4, between the two rings 1 and 2, appear the two gold stars 5 at opposite 25 points. The periphery is perfectly smooth and round.

What I claim is—

The design for a button herein shown and described.

JAMES MADISON CLAYBROOK.
